CLIP LOADING MACHINE

John E. Pool, Washington, D. C., and John W. P.
Beaver, Alexandria, Va.

Application January 14, 1947, Serial No. 722,014

2 Claims. (Cl. 86—48)

(Granted under the act of March 3, 1883, as
amended April 30, 1928; 370 O. G. 757)

1

The invention described herein may be manufactured and used by or for the Government for governmental purposes, without payment to us of any royalty thereon.

This invention relates to an article loading machine, and more particularly it is directed to a device of this character for expeditiously loading conventional blasting caps into waterproof clips of the type disclosed in my co-pending application Serial No. 619,271, filed September 28, 1945.

Blasting caps heretofore were loaded into clips by inserting the open ends of the blasting caps into engagement with an extremity of the clips and forcing back the other extremity thereof.

This loading of the clips with the blasting caps is an operation which at present has to be performed by hand, and which is liable to involve loss of valuable time.

The object of the present invention is to obviate or avoid this disadvantage, and it consists of a machine which is capable of having the clips applied thereto and which enables clips to be mechanically expanded, permitting the blasting caps to be readily loaded into the clips.

Still another object of the invention is to provide a device of the class described which is simple in operation, inexpensive to manufacture and not liable to get out of order.

With the above and other objects and advantages in view, the invention consists of certain features of construction and operation of parts which will hereinafter be described and shown in the following drawings, in which:

Fig. 1 is a side elevation, with the clip loading machine in an inoperative position;

Fig. 2 is an end view thereof looking in the direction of the arrow *a*;

Fig. 3 is a fragmentary side elevation showing the device about to engage a flange on the extremity of a clip;

Fig. 4 is a similar view to Fig. 1 showing the machine in an operative position;

Fig. 5 is a longitudinal sectional view showing the device engaged with a flange of the clip;

Fig. 6 is a longitudinal view of the machine, the parts of which being in the same position as in Fig. 4;

Fig. 7 is a plan view of the device looking in the direction of the arrow *b*, Fig. 4;

Fig. 8 is a detail transverse sectional view taken on line VIII—VIII of Fig. 5;

Fig. 9 is a detail vertical view taken on line IX—IX of Fig. 5;

2

Fig. 10 is a detail sectional view similar to Fig. 5, and

Fig. 11 is a detail transverse sectional view taken on line XI—XI of Fig. 10.

5 Referring more specifically to the drawings, a supporting frame indicated generally by 1 is provided, comprising dual vertically extending side plates 2, Fig. 2, with outwardly extending lower flanges 3 adapted to be bolted to any suitable support (not shown). The upper edges 4 of the side plates 2 slope upwardly and a bed or base plate 5 is mounted by screws 6 in the side plates 2 in the same sloping plane and flush with the upper edges 4 thereof. The sloping angle of the base plate 5 provides for ease in placing an empty cap clip into position and removing the loaded clip from the machine.

A movable holding block 7 is adjustably mounted in a slot 8 provided in the lower end of the

20 base plate 5 and a group of fixed fingers or pull hooks 9 are fastened on the front end of the holding block 7 by means of a pin 11, with the holding block 7 being movably mounted between upwardly extending portions 12 provided on the

25 lower ends of side plate 13. The holding block 7 is adjustably actuated between the upwardly extending portions 12 by means of an adjusting screw 14 which extends through an end plate 15 mounted on the lower end of the bed plate 5 by

30 screws 16, with the inner end of the adjusting screw 14 abutting against the bed plate. An adjusting nut 17 is mounted on the lower end of the movable holding block 7, which is adapted to slide in the slot 8 formed in the lower end

35 of the bed plate 5, as more particularly shown in Fig. 8. The side plates 13 are mounted on the bed plate 5 by screws 19 and have upwardly extending portions 20 provided on the upper ends thereof for a purpose which will hereinafter appear.

A pair of spaced side plates 21 are mounted on the upper end of the base plate 5 by means of screws 22, which side plates 21 furnish bearings for a cam shaft 23 on which is mounted an arcuate-shaped cam 24 with rounded edge portions 25 and 25'. The cam 24 is adapted to engage a substantially rectangular-shaped, cut-out portion 26 having a cam surface 26' including a curved indented surface portion 27 of a cam follower

45 plate 28. The cam follower plate 28 is provided with an inwardly extending arm 29 having an elongated slot 30 therein, which engages a pivot pin 31 fastened to the upper side plates 21. On the inner end of the cam follower plate 28 are a 50 pair of fingers or pull hooks 32 held in spaced

relation by means of spacer blocks 33 and secured to the inner end of the cam follower plate 28 by a rivet 34 and a clamp bolt 35.

A cam lever 36 is mounted at one end to a bushing 37 mounted on the cam shaft 23, which cam lever 36 is provided for turning and reversing the cam 24 through the arc required to operate the cam follower plate 28 for operating the pair of pull hooks 32 for a purpose which will hereinafter be described. Set screws 38 are provided on the bushing 37 for adjusting the lever 36 on the cam shaft 23.

The clips used in carrying out the invention are of the type disclosed in the co-pending application Serial No. 619,271 and include turned extremities 39 and 39' to define channels 40 and 40' respectively with the body of the clips. The clips may be secured together in back-to-back relationship to provide dual clips 41 and 41' as in Figs. 5 and 9 or they may be single as the clip 42 in Figs. 10 and 11.

In operation, using dual clips 41 and 41' in back-to-back relationship, the empty clips are placed on the machine between the upwardly extending portions 12 and 20 of the side plates 13, with the lower clip 41' engaging the bed plate 5. The extremity 39' of the upper clip 41 is inserted under the pull hooks 9 on the holding block 7 in the lower end of the bed plate 5. Referring to Fig. 1 which shows the machine in an inoperative position, the lever 36 has been actuated in a counter-clockwise direction or to the left, which causes the cam 24 to be rotated in the same direction for operating the follower plate 28 in such a manner as to cause the pull hooks 32 on the inner end thereof to be in a raised position. Upon rotating, the lever 36 a predetermined distance in a clockwise direction, the cam 24 is rotated in the same direction until the rounded edge portions 25 and 25' thereof engage certain sides of the substantially rectangular-shaped, cut-out portion 26 of the follower plate 28, whereby the inner end of the follower plate is caused to move in a forward and downward direction as shown in Figs. 3 and 5, with the pull hooks 32 extending above and beyond the extremity 39' of the upper clip 41. Upon rotating the lever 36 still further to the right until the rounded edge portion 25' of the cam engages a corner 43 of the substantially rectangular-shaped, cut-out portion 26 of the follower plate 28, the follower plate is actuated to cause the front end thereof to move still further downwardly and to begin its rearward motion, whereby the pull hooks 32 are caused to engage the extremity 39' of the upper clip 41 as illustrated in Fig. 5. Still further movement of the lever 36 to the right causes the follower plate 28 to move rearwardly, whereby the pull hooks 32 grip and pull on the extremity 39' of the upper clip 41 which spreads the extremities 39 and 39' of the upper clip 41 apart or to be spread outwardly. A slight further movement of the lever 36 causes the rounded edge portion 25' of the cam 24 to engage in the indented cam surface portion 27 of the cam surface 26' of the follower plate 28 which locks the follower plate 28, thereby holding the upper clip 41 by means of the pull hooks 32 in a safe and convenient position for laying blasting caps 44 into place in the upper clip 41 as illustrated in Fig. 6.

Reversing the motion of the lever 36 to the left or in a counter-clockwise direction, the follower plate 28 is unlocked and the operation

of the parts is reversed as described above, which permits the extremities 39 and 39' of the upper clip 41 to spring back into their original position for retaining the blasting caps 44 in the upper clip 41. The dual clips 41 and 41' are then removed from the machine and placed on the machine in a reversed position, with the loaded clip 41 on the bottom and the empty clip 41' on top after which the operation is repeated as above described. During the actuation of the follower plate 28 by the cam 24, the slot 30 provided in the follower plate is moved on the pivot pin 31 until the pin engages an end of the slot 30.

To employ a single clip 42 in the machine, a spacing block 45 is used which has the same depth as the clip as illustrated in Figs. 10 and 11. By adjusting the block 7 in the slot 8 in the lower end of the bed plate 5 either in a forward or rearward direction by means of the adjusting screw 14, different size cap clips may be used in the machine.

It will thus be seen that there has herein been provided a novel and efficient form of device for loading blasting caps which is well adapted for the purpose intended. Even though there has herein been shown the device as comprising certain features of construction and operation of parts, it is nevertheless to be understood that various changes may be made therein, if the changes do not depart from the spirit or scope of the claims.

Having thus described our invention, what we claim and wish to secure by Letters Patent is:

1. A machine for loading clips having extremities cooperating to receive and retain blasting caps, comprising a support, an adjustably mounted block, pull hooks mounted on said block, said pull hooks adapted to engage one extremity of the clips, and manually actuated means including a cam shaft, a cam mounted on said shaft and a follower plate actuated by said cam, said follower block coacting with the other extremity of the clips for spreading the extremities of the clips apart, whereby the blasting caps may be loaded in the clips which are actuated by the cam follower plate for releasing said extremities whereby the caps are retained in the clips.

2. A machine for loading clips having extremities cooperating to receive and retain blasting caps, comprising a support, an adjustably mounted block, pull hooks mounted on said block, said pull hooks adapted to be engaged by one extremity of the clips and manually actuated means including a cam shaft, a cam mounted on said shaft, a follower plate actuated by said cam, and pull hooks mounted on one end of said follower plate, said follower plate adapted to be actuated by said cam for causing the last-mentioned pull hooks to coact with the other extremity of the clips for spreading the extremities of the clips apart, whereby the blasting caps may be loaded in the clips which are actuated by the cam follower plate for releasing said extremities, whereby the caps are retained in the clips.
